UNITED STATES PATENT OFFICE.

WINFIELD S. GREENING, OF DECATUR, ASSIGNOR, BY DIRECT AND MESNE ASSIGNMENTS, TO DAVID BLALOCK, OF MACON COUNTY, ILLINOIS.

SASH-CORD GUIDE.

SPECIFICATION forming part of Letters Patent No. 280,609, dated July 3, 1883.

Application filed January 15, 1883. (Model.)

To all whom it may concern:

Be it known that I, WINFIELD S. GREENING, a resident of the city of Decatur, county of Macon, and State of Illinois, have invented 5 certain new and useful Improvements in Sash-Cord Guides, of which the following is a full, clear, and exact specification.

The object of my invention is to produce a cheap and effective sash-cord guide that can 10 be attached to a window-frame at a nominal expense, and by means of which the weights may be adjusted to operate at various positions relative to the sides of said frame.

My invention consists in a metallic arm provided with a longitudinal slot that carries a 15 pair of adjustable guide-pulleys provided with a rabbeted face-plate that fits between the sash-pulley frames, and provided with a combined brace and anchor that rests in a groove in the studding and supports the arm both vertically 20 and horizontally.

In the drawings accompanying and forming a part of this specification, Figure 1 is a side elevation of my device as attached to a window-frame, said frame and adjacent studding appearing in section, and but one cord and weight being shown. Fig. 2 is a top view of 25 my device. Fig. 3 is a section on dotted line xx in Fig. 1; and Fig. 4 is a sectional view of 30 the casing on dotted line yy in Fig. 1, showing the top of an end of my device.

a is the arm, provided with slot a' , in which pulleys b b are adjustably supported.

b b are bolts that secure pulleys b b in position on the arm, and by means of which said pulleys are adjusted.

c is a combined brace and anchor that rests in groove o , and prevents any lateral disadjustment in the arm.

d is the face-plate that closes the opening through which arm a is inserted.

d d are rabbets on face-plate d , in which the edges of the sash-pulley frames e e fit, and by means of which the arm is secured longitudinally.

f is the cord, and g the weight ordinarily used.

h is the casing or jamb of the window-frame.

i is the studding.

m is the opening through which arm a is inserted.

In attaching my device to a window, I start a two-inch hole directly in the center of the ordinary position of the sash-pulleys, and continue the same through casing and studding 55 until a space sufficient to admit arm a is cleared. Then I form slot o and countersink the face of the jamb to receive the face-plate d and pulleys e e . My cords are then placed in position in the pulleys, the weights pushed through 60 the opening m , arm a placed in position, and the whole secured by pulley-frames e e , which are fitted and attached in the ordinary manner.

In case it is found necessary to use a weight 65 so heavy that by its extreme length it cannot be made to pass through opening m , I substitute a series of short weights, as indicated in the drawings. As the distance between the sides of a window-frame and the adjacent studding is not uniform, and as the width of the studding varies, it follows that a practical sash-cord guide must have its guide-pulleys so constructed as to be easily adjusted.

In my device, when the position and size of 75 the studding are ascertained, and the proper position of the weights established, pulleys b b are readily adjusted by means of bolts b b in slot a' .

It will be noticed that the vertical sides of arm 80 a approach each other toward the rear end of the same. This arrangement has the effect of bringing the pulleys b b close together, so that the weights can operate without danger of coming in contact with the walls. As the weights 85 have a tendency to force pulleys b b outward, it is apparent that the beveled construction of said arm above mentioned is of utility in assisting the bolts in overcoming said tendency.

I do not use any screws or substitutes in attaching my device, but simply rely on the ordinary sash-pulley frames to hold the same in position.

I claim—

Arm a , provided with slot a' , support c , and 95 face-plate d , in combination with pulleys b b , as and for the purpose set forth.

WINFIELD SCOTT GREENING.
